Israel Correll Treadarawas Co. Ohio

Salters Patent

The device referred to in this Slaters Patent is a making part of the same containing a description in the words of the said Israel Correll himself of his improvements in the grain stone setting machine.

I do know that Israel Correll of the County of Treadarawas and State of Ohio late deceased invented a grain setting machine which is described as follows. The machine consists of the following principal parts (etc). The frame of this machine is a square frame of about three feet in length, two feet in width to the clear the middle. The end posts are made of square timber of two and two and a half inches square and the side posts one and a half inch thick and thirteen inches wide and they are framed into the front posts just from the bottom of said post. The upper front post is mortised into the front just above the side joint the two front joint mortised into the post just below the side joint the hand lever joint mortised into the post just below the side joint the upper hand post to be mortised through the post eleven inches from the head one end of the hand post to extend his feet above the side joint and another of the same length and size to form the carriage on the wheel and a cap across the top and an ^{upper} ~~upper~~ post at the bottom to hold the iron post form for a wheel fastenings and machine. A cylinder ten inches diameter shaft running through the side frame (airing) to just below the cylinder on each side a half at each end for the journals that four inches left square at each end to receive the paddles which makes the shaft the full 11 inches long to cylinder to be turned perfectly true and correct and with every end open. The shell is caused to be in a circular form to admit about the cylinder and to surround the third or four fourth cylinder and the shell emerges into the said shell a cylinder being at the upper edge by the means of two side plates to regulate the concrete grain cylinder. This a very good fit in the inside of the shell just below the shell end and then with the stones running through the said joint to let the lower edge of the concrete the above amount of stones being with a roller at each end to carry the grain to the said machine with each a pulley on the bottom of the roller. After the stone has
